(57) **CLAIM**

The ornamental design for a display screen with a graphical user interface for auto-regulation of cerebrovascular perfusion, as shown and described.

DESCRIPTION

FIG. 1 is a front view of a first embodiment of a display screen with a graphical user interface for auto-regulation of cerebrovascular perfusion in accordance with the present disclosure; and,

FIG. 2 is a front view of a second embodiment of a display screen with a graphical user interface for auto-regulation of cerebrovascular perfusion in accordance with the present disclosure.

The broken line showing of text and other graphical user interface elements is for the purpose of illustrating portions of the article and forms no part of the claimed design. The broken line showing of a display screen is for the purpose of illustrating environmental structure and forms no part of the claimed design.

1 Claim, 2 Drawing Sheets
